UNITED STATES PATENT OFFICE.

STANLEY P. LOVELL, OF BROCKTON, MASSACHUSETTS.

COLLOID-TREATED FABRIC.

1,256,240.

Specification of Letters Patent. Patented Feb. 12, 1918.

No Drawing.

Application filed June 27, 1917. Serial No. 177,387.

To all whom it may concern:

Be it known that I, STANLEY P. LOVELL, citizen of the United States, residing at Brockton, in the county of Plymouth and 5 State of Massachusetts, have invented new and useful Improvements in Colloid-Treated Fabrics, of which the following is a specification.

My invention is a new treated fabric in 10 or on which colloidal substances are deposited in a finely comminuted or porous form and retained thereon and therein by engagement of the particles of colloidal substance with the fibers of the fabric and 15 with each other, and my invention also includes a method of producing this treated fabric. This new fabric may be of woven material, such for example, as cotton cloth, or of structureless material, such as felt or 20 paper and is impregnated or coated with a colloidal substance, such for example, as nitro-cellulose, casein, albumen, various gums, resins or rosin.

This fabric I produce in the following 25 manner: Taking a sheet of the material that it is desired to treat it is treated in a dipping tank, or other suitable receptacle, with the colloidal substance to be used (for example some of the substances mentioned above), 30 the colloidal substance being diffused or dissolved in a suitable medium, such for example as alcohol, acetone, ether, ammonia solution, etc. To persons skilled in this art the suitable medium for the particular solid 35 which is to be used will be known or readily ascertainable from published works of authority. The impregnated or coated fabric is then passed to a water bath as rapidly as may be, in which the impregnated or coated 40 fabric remains until displacement of the solvent liquid is practically completed by the water, which varies in time according to the nature of the solid employed, the nature of the solvent and the substance or body 45 of the fabric employed. For instance, nitro-cellulose in acetone on light weight cotton cloth will require perhaps the minimum immersion to effect the displacement of one liquid by the other. It will be unnecessary 50 to elaborate upon the time necessary for immersion, since the ascertainment of the proper time for immersion is easy by simple manipulative tests. Squeezing the treated fabric, if the displacement of solvent is not 55 complete, will bring to the surface particles

or drops of colloid solution, easily identified by its gelatinous character.

The fabric is now withdrawn from the water bath, dried and the solid will be found precipitated in or on the fabric and 60 entangled and interlocked with the fibers thereof.

The new material forms the raw material for a number of distinct uses, and as such a raw material is economically superior to 65 other available materials. As a substitute for leather in stiffening certain parts of a shoe it may be dipped in a suitable solvent and instantaneously the finely comminuted or porous colloidal material is resolved into 70 a coalescent, flaccid body which may be instantly placed and conformed and will dry in the desired shape, stiff, flexible and resili- 75 ent. As a material for imitation linen collars and the like, the blank is treated with suitable colloidal material in the sheet, which is precipitated as described; blanks are dried out and each is dipped in solvent and instantaneously the comminuted or porous colloidal material on the surface is 80 resolved into a coalescent, flaccid sheet and the collar may be folded to shape before the solvent is withdrawn by evaporation and will dry in the desired shape to which its resili- 85 ence will restore it, if distorted.

This instantaneous operation of the solvent in the use of my new treated fabric is important in many applications, since it prevents the possibility of destruction of the goods which frequently happens when 90 soaking of the fabric is necessary to prepare the fabric for use, as is usual, for if the soaking be continued too long the solid may be partially or entirely removed and the goods damaged or entirely ruined.

Furthermore, the instantaneous solubility of the solid renders unnecessary the co-ordination of the tempering or preparatory process and the actual working. In older processes where a fabric was tempered or 100 prepared by long continued soaking the workman might get more fabric to the proper temper than he could work up, in which case the surplus was likely to be over-treated and more or less damaged or the 105 workman might be obliged to wait for the goods to arrive at the proper temper. The exact coördination of the tempering process with the capacity of the workman was rarely attained.

I claim:

1. As a new article of manufacture, a fabric whose interstices are filled with powdered colloidal material, insoluble in water, and precipitated therein.
2. The method above described which consists in impregnating a sheet of fibrous fabric with colloidal material, insoluble in water, in diffusion or solution and passing the fabric immediately to a water bath; im-

mersing the fabric therein until the water displaces the solvent, precipitating the colloidal material in the fibrous fabric.

Signed by me at Boston, Massachusetts, this twenty-sixth day of June, 1917.

STANLEY P. LOVELL.

Witnesses:

**JAMES M. HOOPER,
OLIVER MITCHELL.**

DISCLAIMER

1,256,240.—*Stanley P. Lovell*, Brockton, Mass. COLLOID-TREATED FABRIC. Patent dated February 12, 1918. Disclaimer filed March 16, 1934, by the assignee, *Celastic Corporation*.

Hereby enters this disclaimer to that part of said specification which is in the following words, to wit:

“Or paper” (page 1, lines 19, 20); “casein, albumen, various gums, resins or rosin” (page 1, lines 21, 22); “for example, some of the substances mentioned above” (page 1, lines 28 and 29); “ammonia solution” (page 1, lines 32, 33).

Your petitioner hereby enters disclaimer to the subject matter of the claims of said patent 1,256,240, except where a cloth fabric is employed whose interstices are filled with precipitated nitrocellulose in such state of subdivision and porosity that the resulting product is capable of being made flaccid substantially instantaneously by the use of an appropriate solvent, and in that condition is capable of being formed into a desired shape and become stiff, flexible, and resilient in its new form upon vaporization of the solvent.
